PROCESS FOR COOLING FURNACES BY MEANS OF COOLING CHAMBERS

Gustav Dörrenhaus and Simon Walter, Mulheim-Ruhr, Germany, assignors to the firm Vereinigte Stahlwerke Aktiengesellschaft, Düsseldorf, Germany

Application June 9, 1934, Serial No. 729,862
In Germany June 23, 1933

8 Claims. (Cl. 266—32)

The present invention relates to a process, device and arrangement for the cooling of cooling chambers in blast furnaces.

In the already known cooling chambers for the cooling of blast furnaces which chambers are closed in most cases, large quantities of sludge deposit in the cooling chamber and these have constantly to be removed by numerous attendants. If the sludge is not removed in time or if the cooling should fail, the cooling chambers will crack. This will cause the water to flow into the blast furnace with the result that normal working may have to be interrupted. The present invention has the object of ensuring reliable cooling at all times and of reducing the consumption of water. According to the present invention a saving of about 70% of water can be attained in comparison with the cooling systems hitherto in use.

The present invention consists in that the cooling agent is sprayed against the cooling surfaces of an open cooling chamber in a fine spray. The atomizing of the cooling agent in the form of a spray results in the surfaces of the cooling chamber being wetted on all sides which gives a higher degree of efficiency of the cooling surfaces, which up to the present, with the usual flushing systems, were only cooled in ratio to the cooling chamber filling. The atomizing of the cooling agent is most advantageously effected by blowing in compressed air under low pressure (about 0.1—0.2 atm.) into the cooling stream, which is flowing into the cooling chamber or by blowing compressed air through the surface level of the cooling agent filling in cooling chambers of already known systems. In both cases the compressed air not only ensures a very fine atomization of the cooling agent but results also in a particular support due to the fact that the compressed air, when expanding, absorbs heat.

As it is possible to work with very small quantities of water and compressed air, comparatively simple devices will be sufficient. Only a small number of stop-cocks for water are required because there is no need to clean out the cooling chamber; this is due to the fact that no sludge can deposit in the cooling chamber because the compressed air would keep any sludge which might be present suspended in the cooling agent. No special stop-cocks are required for the compressed air conduits, because it is possible to employ simple sealing plugs if it should be necessary to subdivide the compressed air pipings.

For the purpose of carrying out the process, a nozzle can be used for the discharge of the cooling agent stream in the cooling chamber into which nozzle channels connected with the source of compressed air issue in such a way that the jets of compressed air which emerge therefrom atomize the cooling means and spray the same

against the upper wall and the side walls of the cooling chamber. If the compressed air is to be blown through the surface level of the liquid in the cooling chamber, then a compressed air nozzle with channels arranged in a suitable direction is arranged under the surface of the liquid.

The cooling agent can be led through a series of cooling chambers and can be used over and over again, especially because the expansion of the compressed air produces a considerable decrease in the temperature of the cooling agent. The cooling chambers can therefore be connected by simple overflow pipes, in such a way that the overflow water of an upper cooling chamber will flow into the chamber situated below it, where it will be used again for cooling purposes by atomizing and spraying it in a finely divided state against the upper wall and the side walls of the cooling chamber.

This process can be continued until the cooling water has reached the permissible temperature. As the spraying by means of compressed air cools the overflow water always afresh, it can be used for a large number of cooling chambers arranged one underneath the other.

According to the present invention cracked cooling chambers can still be used in that chambers are inserted into them which are cooled according to the present invention and transmit their low temperature to the cracked chambers.

The present invention has therefore a number of advantages, namely:

1. About 70% saving in cooling means.
2. A smaller number of attendants are required.
3. Safer working, because the cracking of cooling chambers is eliminated and there is no danger of water entering the furnace.
4. Less weight of the cooling chamber, due to a higher degree of efficiency of the cooling surfaces.

The power required for atomizing the air is very low. With a pressure of, for example, 0.8 atm. wind pressure in a blower having a capacity of 1000 cbm. wind per minute, only about 60 cbm. wind are required for 750 cooling chambers of a blast furnace of a capacity of 400 tons iron per day, in order to produce the atomization, which is about 6% of the capacity. This additional output can be obtained if the usual number of revolutions of the machine is increased by a few revolutions.

The new cooling process has been practically used for a considerable time at a furnace having a capacity of 400 tons per day. None of the cooling chambers has been damaged therein during the whole working period. Furthermore, the furnace consumed only 2 cubic meters of cooling water per minute in comparison with a

consumption of 7 cubic meters per minute in the already known cooling processes by means of a water stream passing through closed cooling chambers. In carrying out the new process only 5 half of the number of attendants were required, namely a single person each time, compared with the formerly required two persons for attending the cooling process. In spite of using muddy river water no sludge has been deposited in the cooling 10 chambers so that a removal of sludge was entirely superfluous and a continuous and uniform cooling of the whole shaft of the furnace and in consequence thereof a regular working of the furnace without any troubles was obtained.

15 In the accompanying drawing the present invention is more clearly described by means of examples. In the drawing

Fig. 1 is a section through a cooling chamber and a water nozzle

20 Fig. 2 is a side elevation of a part of the furnace wall with the arrangement of the cooling devices

Fig. 3 is a cross section according to line III—III of Fig. 2

25 Fig. 4 is a section of a cooling chamber which is inserted in an original cooling chamber which is damaged at two places.

In Fig. 1 a cooling chamber 1 is shown having an inserted water inlet or nozzle 2, at the lower 30 end of which compressed air, coming from the pipe 3 is so guided through channels 4 against the emerging stream of water, that the latter is sprayed, i. e., atomized to a very high degree. The surplus cooling water flows through the overflow 35 5 and can then be used again in the other cooling chambers of the furnace arranged below it.

The said utilization of the surplus water will be apparent from Fig. 2. The cooling water is 40 fed by the conduit 6 to the single segments 1a, 1b, 1c etc. of the armour of the furnace and flows through the pipe lines 8a, 8b, 8c etc. of sufficient dimensions to the distributing troughs 9a, 9b, 9c. From these troughs the cooling water flows 45 through the pipe lines 10a, 10b, 10c etc. to the cooling chambers 11a, 11b, 11c etc. of the two upper ranges. As is to be seen from Figure 2 the several tubes are supported upon the cooling chamber. For instance the tube 2 for feeding water may be secured thereto and the tube 3 for feeding air may be linked to the tube 2. Instead of having the tubes suspended to the cooling chamber it would, of course, also be possible to support them upon the housing of the furnace 50 or upon the stagings around the furnace. In these cooling chambers the water is atomized by means of the air fed through the conduits 12 and sprayed against the surfaces of the cooling chambers. The water flowing over the cooling chambers 55 11a, 11b, 11c etc. passes through the pipes 13a, 13b, 13c etc. to the cooling chambers 14a, 14b, 14c etc. of the third and fourth range and so on, in which cooling chambers it is atomized in the same manner as before. When the cooling water has reached its highest admissible temperature, for ex. after having been used in 10-15 ranges of cooling chambers lying one below the other, it is carried off by the collecting pipe line 15, and fresh cooling water is fed to the following ranges of cooling chambers by the pipe line 16 and the distributing troughs 11a, 11b, 11c etc.

The above described distributing arrangement is shown in section in Fig. 3.

In Fig. 4 a special application of the invention is shown in that case where the original cooling chamber 18 is cracked for example at 19 and 20. In this cooling chamber 18 another cooling chamber 23 is then inserted which is filled with 5 water and provided with an air inlet 21 by means of which air is blown through the surface 22 of the water and sprayed thereby against the walls of the cooling chamber 23.

What we claim and desire to secure by Letters 10 Patent of the United States of America is:

1. A process for cooling furnaces by means of cooling chambers, in which the cooling agent is sprayed in atomized condition against the cooling surfaces of the cooling chamber by means of compressed air. 15

2. A process for cooling surfaces by means of cooling chambers, in which the cooling agent is sprayed in atomized form against the cooling surfaces of the cooling chamber by means of air 20 under a pressure of about 0.1-0.2 atm.

3. A process for cooling furnaces by means of cooling chambers in which a cooling stream is introduced into the chamber and a stream of air is caused to act upon said cooling stream under 25 a pressure of about 0.1-0.2 atm. so that the cooling agent is atomized and sprayed against the cooling surfaces of the cooling chamber.

4. A process for cooling furnaces by means of cooling chambers in which a cooling stream is 30 introduced into the chamber and air under a pressure of about 0.1-0.2 atm. is blown in an upward direction through the surface level of the cooling agent so that the cooling agent is atomized and sprayed against the cooling surfaces 35 of the cooling chamber.

5. A cooling chamber for cooling blast furnaces, provided with a nozzle for introducing the cooling agent, in which compressed air channels are arranged to introduce jets of compressed air 40 which atomize and spray the cooling agent.

6. A cooling chamber for cooling blast furnaces, provided with a nozzle for compressed air which is arranged under the surface level of the cooling agent which is in the cooling chamber, 45 the said nozzle being arranged to blow in air which sprays the cooling agent against the surfaces of the cooling chamber.

7. An arrangement for cooling blast furnaces, comprising a plurality of cooling chambers arranged in the wall of the furnace in several rows one below the other, supply pipes for the cooling agent, the said supply pipes being connected with the upper rows of the cooling chambers, connecting pipes between the upper and lower rows 50 of cooling chambers for leading the overflow cooling agent, and air supply pipes connected with the cooling chambers for supplying compressed air to the same. 55

8. An arrangement for cooling blast furnaces, comprising a plurality of cooling chambers arranged in the wall of the furnace in several rows one below the other in checked formation, supply 60 pipes for the cooling agent, the said supply pipes being connected with the two upper rows of cooling chambers, connecting pipes between the upper and lower rows of cooling chambers for leading the overflow cooling agent, the cooling chambers of each row being connected with that of each 65 second row below it and air supply pipes connected with the cooling chambers for supplying compressed air to the same.

GUSTAV DÖRENHAUS.
SIMON WALTER.
